TELEVISION FILING TAPE CONTROL UNIT

Charles F. Grossman, Sunnyvale, Calif., assignor to
Ampex Corporation, Redwood City, Calif., a cor-
poration of California

Filed Nov. 18, 1966, Ser. No. 4,733

Term of patent 14 years

(Cl. D26—5)

FIG. 2

FIG. 3

FIGURE 1 is a front and right side perspective view of a television filing tape control unit, showing my new design;

FIGURE 2 is a rear and right side perspective view thereof; and

FIGURE 3 is a right side elevation view, the left side being a mirror image thereof.

I claim:

The ornamental design for a television filing tape control unit, substantially as shown and described.
